UNITED STATES PATENT OFFICE.

CHARLES WIPFLER, OF DETROIT, MICHIGAN, ASSIGNOR TO THE ART STOVE COMPANY, OF SAME PLACE.

DESIGN FOR A COOKING-STOVE.

SPECIFICATION forming part of Design No. 22,447, dated May 16, 1893.

Application filed April 14, 1893. Serial No. 470,377. Term of patent 7 years.

To all whom it may concern:

Be it known that I, CHARLES WIPFLER, a citizen of the United States, residing at Detroit, county of Wayne and State of Michigan, have invented and produced a new and original Design for Stoves; and I declare the following to be a full, clear, and exact description of the invention, such as will enable others skilled in the art to which it appertains to make and use the same, reference being had to the accompanying drawing, which forms a part of this specification.

The leading features of my design consist in the ornamental surfaces and general outlines, as herewith illustrated and described, the drawing submitted herewith being a view in perspective, in which—

A represents a leg frame, ornamented with scroll-work, the same being constructed with an upper rim, as at "a," ornamented with vertical indentures or grooves, and also with a lower beaded rim, as at "a'."

A' are the legs, the upper portions of which are ornamented with scroll-work.

B denotes an oven door, constructed with an outwardly projecting surface, ornamented about the border thereof with scroll-work. In the center of the door is a representation of a head in alto relieveo, surrounded by a shield or plate ornamented with scroll work, in which predominate parallel scroll lines filled in between with points.

C denotes the side or end of a water tank, ornamented with scroll work and located rearward of the oven door.

D is the end of the ash-pit, ornamented with scroll work.

E is the end of the fire chamber, also ornamented with scroll-work.

F is the upper plate or covering of the stove. 40 Above said covering is a heating chamber G, ornamented with scroll-work, and provided with a damper "g." Above said chamber is a flue H, provided on each side with brackets H' and H² of scroll-work at the upper and 45 lower ends, connected with beaded lines. The face of the flue is ornamented with scrolls in the corners, connected by beaded lines, the whole forming a border about a plane surface on the interior of said border. Above the 50 flue H is a plate I, surmounted, preferably, by a heating chamber J, the face of which is provided with doors J' and J², each ornamented with a border of scroll work, within which is a central shield or plate of scroll work, in which parallel lines of scroll work 55 predominate. The center of each of said shields or plates is ornamented with a circular star-shaped figure.

Above the heating chamber is an ornamental bracket K.

What I claim is—

The design for a stove substantially as herein shown and described.

In testimony whereof I sign this specification in the presence of two witnesses.

CHARLES WIPFLER.
